UNITED STATES PATENT OFFICE.

JOHN F. WHITE, OF CHICAGO, ILLINOIS, ASSIGNOR, BY MESNE ASSIGNMENTS, TO
WHITE PRODUCTS COMPANY, OF CHICAGO, ILLINOIS, A CORPORATION OF ILLI-
NOIS.

LATCH AND KEEPER.

1,334,575.

Specification of Letters Patent. Patented Mar. 23, 1920.

Application filed April 6, 1917. Serial No. 160,102.

To all whom it may concern:

Be it known that I, JOHN F. WHITE, a citizen of the United States, residing at Chicago, in the county of Cook and State of Illinois, have invented certain new and useful Improvements in Latches and Keepers, of which the following is a specification.

In the latching of engine hoods for automobiles, it is important to provide for a certain degree of flexibility of the parts to accommodate the same to the vibrations and strains of use, and at the same time to provide for accurate adjustment of the latch and keeper and associated elements so that there shall be no lost motion and consequent rattling.

It is found that there is considerable variation as between the fit and movement of the hood door and engine frame in cars of the same make and style, and it is a task of some importance to so properly adjust the latch and keeper to each other and to the door and frame that they will engage with certainty when the door is closed and that there shall be such accurate fit as will preclude lost motion when latched.

The object of the present invention is to provide a keeper for coöperation with a hood latch, or other latches where similar conditions are present, the keeper being of such design as to be readily adapted to different types of frame and hood, and which after being assembled with the door and latch may be readily adjusted as to the operative portion of the keeper so as to bring about an accurate coöperative relationship to the latch.

A further object of the invention is the special construction and arrangement of latch elements of the general type set forth in my copending application Serial No. 140,005, Patent No. 1300796, whereby the latch may coöperate with its keeper to effect flexibility and accurate fitting of the parts as above stated; providing for sufficient play of the parts in the act of latching the door to insure engagement with the keeper and to preclude malformation or disarrangement of the latch or keeper if the door be violently closed; also providing for the effective guiding of the latch into engagement with the keeper, and for minimizing wear and insuring ease of operation at all times.

To assist in a thorough understanding of

the invention, a preferred embodiment of 55 the same is set forth in the accompanying drawings, together with certain modifications, the drawings serving as a basis for the following detailed description. The invention being clearly disclosed, it is obvious that 60 other embodiments of the same will readily occur to workers in the art, which, come within the scope of the invention as set forth in the appended claims; wherefore it is understood that the drawing and description 65 are to be taken in an illustrative and not in an unnecessarily limiting sense. In the drawings—

Figure 1 is a perspective view of a keeper embodying the invention; 70

Figs. 2 and 3 are similar views showing the keeper modified to the extent of having the base portion shortened to varying extent;

Fig. 4 illustrates the form of keeper 75 shown in Fig. 3 with its base portion bent to adapt it for fitting over the corner of the engine frame;

Fig. 5 is a similar view of a modified 80 form of keeper designed for use in connection with certain types of hood and machine frames;

Fig. 6 is a fragmentary detail vertical section illustrating the form of keeper shown in Fig. 5 as applied in position; 85

Fig. 7 is an assembled view in side elevation illustrating the keeper and latch in co-operative relation to each other and to the engine hood and frame;

Fig. 8 is a front elevation of Fig. 7; and 90

Fig. 9 is a fragmentary horizontal view through an engine hood showing the relation of the keeper to the engine hood and frame, the keeper here illustrated being the same as shown in Figs. 1 and 2. 95

Referring first to that form of construction illustrated in Figs. 1 to 4 inclusive, it will be understood that from an oblong blank of metal the central portion is punched out along a line substantially parallel to the 100 sides and one end and transversely bent along a line joining the two parallel lines of severance so as to provide a base portion 11 suitably apertured as at 12 for the accommodation of screws, bolts or other securing 105 devices, and another outstanding latch-engaging loop portion 13 which is pendent from the base and reversely bent to a modi-

fied S-shape, the terminal portion 13^a thereof bearing the cross bar 13^b in a substantially vertical position.

In Fig. 1 the base portion 11 is shown as including the full length of the metal punched out of the loop portion 13, whereas in Fig. 2 it is shown as cut off along a line in the vertical plane of the vertical face of said loop portion, and in Fig. 3 it is cut 10 to an intermediate length.

The extent to which the base portion 11 will be cut away will depend upon the situation in which the keeper is to be used. The end of the keeper base will ordinarily 15 bear against the guide plate 14 of the engine frame 15 as indicated in Figs. 7, 8 and 9, and where the engine hood is of a sloping construction, keepers will be employed having a different length of base as shown, for instance, in Fig. 9.

Having reference to Figs. 5 and 6, the blank of metal is entirely punched out at 16 to provide the loop portion 17 having an opening in its upper end only. The 20 lower reversely curved portion of the up-standing part of the keeper is of solid metal except that it is punched out as indicated at 18 in order to weaken the same for transverse bending at the point 19. The base 25 portion of the keepers shown in Figs. 5 and 6, having the reference numeral 20 applied thereto, is likewise suitably apertured at 21 for the accommodation of a fastening device, in this instance shown as a machine 30 screw 22. This form of keeper is particularly adapted for use in connection with that form of engine hood having a doubly hinged portion 23 which is intended to be swung inwardly and then dropped downwardly 35 into a recess 24 between the angle member 25 of the machine frame and a suitable secondary lateral abutment. In such a situation, the base 20 of the keeper is passed beneath and secured to the under side of the 40 frame member 25 with a part 26 of the loop portion of the keeper forming the opposite wall of the recess 24. This is clearly shown 45 in Fig. 6.

When the keeper is mounted as shown in 50 Figs. 7 and 8, for coöperative relation with the hood latch, the base 11 having been cut off of such length as to properly position the loop portion of the keeper with reference to the hood, it will be readily understood that 55 by reason of the peculiar outline and curvature of the loop portion of the keeper, the same may be varied as to height by tapping with a hammer upon the top of the cross bar 13^b which will serve to emphasize the 60 reverse curves of the keeper and reduce its height. If too low, the handle of a wrench or other tool may be inserted within the loop and used as a lever to force the same upwardly increasing its height by slightly 65 straightening the curves. If the cross bar

13^b is too far to the right or to the left to properly engage the hook of the latch, a blow with a hammer on either side will properly position the same; or the jaws of a wrench may be closed upon the portion 13^a 70 of the keeper and the degree of the S-curve may be emphasized or minimized in order to properly position the cross bar 13^b for co-operative engagement with the hook of the latch. 75

It has been found that where the latch is rigidly mounted upon the hood, the violent slamming of the hood to its closed position will cause the head of the latch to strike upon the cross bar 13^b of the keeper and 80 tend to displace the same from its proper position after a time. On the other hand, it has been found to be disadvantageous at times to have the latch movably mounted upon the hood, that is to say without restraint as to its swinging motion. With a view, therefore, to harmonizing these conditions I have devised a latch of the same general type as that set forth in my copending application Serial No. 140,005, but with 85 the hook limited as to its swinging movement relative to the hood, the present latch comprising a shank 30 pivoted at 31 to the handle 32, the said shank being of round stock and having formed thereon a hook 33 90 for engagement with the cross bar 13^b of the keeper, the hook head of the latch having a terminal portion 34 forming an exterior continuation of the beak portion of the hook with a gradual curve adapted to guide the 100 descending hook into a proper position to engage within the keeper. It will be understood that the latch as a whole swings inwardly and outwardly with the hood door 35, but the lower portion thereof also has a 105 movement independently of the door toward and from the door and keeper, the extent to which it may move away from the door being limited by the loop bracket 36. A spring 37 is mounted about the latch 110 shank 30 between the loop bracket 36 as a lower abutment and the shoulder 38 as an upper abutment whereby the hook is normally pressed by the spring upwardly longitudinally of its axis away from the keeper 115 so as to hold the same securely in engagement after the hook is once entered within the keeper. Similarly to the construction set out in my application above referred to, an operating member 39 is pivoted to the handle at 40, this operating rod having its lower portion formed as a loop with a cross member 41 lying within the throat of the hook and below the beak thereof. 120

The operation of the latch is the same as 125 that described in my copending application, that is to say, assuming the hood to be closed and latched with the parts in the position shown in Figs. 7 and 8, an upward pull upon the handle 32 in the natural act 130

of opening the hood serves to lift upwardly on the operating rod 39 and to push downwardly upon the shank 30 of the hook latch. The cross member 41 will assist to expel the 5 cross bar 13^b of the keeper from out the throat of the hook over the beak 33 and at the same time will tend to pull the lower hooked end of the latch to the right out of engagement with the keeper. Assuming the 10 hood door to be dropped in its lowered position ready for latching, a downward pressure upon the handle 32 will tend to push the hook of the latch to the left and also to move the latch downwardly in opposition to the spring 37, the cross bar 13^b of the keeper 15 riding upon the curved surface of the hook extension 34 and as soon as the beak 33 of the hook clears the said cross bar 13^b the hook will snap into engagement with the keeper.

20 There is considerable wear upon the cross member 41 of the operating rod loop and also upon the beak of the hook. Where these parts are made of flat stock, punched out of sheet metal, this wear is a serious 25 item. By making these parts of round stock as illustrated, the wearing contact is spread over a much larger surface and is reduced to a negligible quantity.

If it be assumed that the hood is dropped 30 into its closed position but is not yet latched, an inexperienced or rough manipulator of the same is liable to attempt to latch the hood by slamming the door. It will be clear that if the hook shank 30 were guided with- 35 in a bracket at its lower end which did not provide for lateral movement, the impact of the hook against the keeper would tend to displace the latter inwardly and would cause the same after a time to become inoperative 40 for coöperative relation with the latch. By means of the present construction, if the hood were slammed shut, the hook of the latch can yield toward the door to such an extent that however strong pressure be ap- 45 plied to the door no pressure would be trans- mitted to the keeper by reason of the swing- ing of the latch toward the door. This effectually prevents any malformation of the parts. The loop bracket 36, at the same 50 time, limits the movement of the latch in- wardly away from the door and the latch being maintained under the influence of the spring 37 will, after being engaged within the keeper, hold the door 35 firmly against 55 the guide plate 14 so as to preclude any mis- fit or rattling of the parts.

It will thus be seen that the appropriate 60 form of keeper having been chosen for the latching of the hood, and secured in place by the machine screws 22 or suitable secur- ing device, the relation of the cross bar 13^b of the keeper may be readily adjusted by bending the same inwardly or outwardly, or upwardly or downwardly to suit the par- 65 ticular mounting of the latch upon the hood

or the relation of these to the frame and guide; further that this adjustment having been secured, the special arrangement of the latch, whereby violent impact is prevented, insures a maintenance of the adjustment 70 even under rough usage.

I claim:

1. A keeper comprising a fixed base and an outstanding latch-engaging portion in- 75 cluding a cross-bar, the latch engaging por- tion bent from a straight line whereby to enable it to yield toward the base to vary the effective length thereof.

2. A keeper comprising a fixed base and an angularly disposed outstanding latch-en- 80 gaging loop portion, the latter bent along a curved line whereby to enable it to yield toward the base and at right angles thereto to vary the effective length thereof.

3. A keeper comprising a fixed base and 85 an angularly disposed outstanding latch-en- gaging loop portion, the latter bent in a re- verse curve whereby to enable it to yield in two directions at angles to each other to vary the effective length thereof. 90

4. A keeper comprising a blank punched out at one end and the punched out mate- 95 rial transversely bent to form a fixed base and the remainder an angularly disposed outstanding latch-engaging loop portion, 95 the latter bent in a reverse curve whereby to enable it to yield toward the base and at an angle thereto to vary the effective length thereof.

5. In a hood fastener or the like, the com- 100 bination with a hinged member to be latched, of a keeper fixedly mounted within the hood, a latch carried by the hood door and mounted to swing with and independ- 105 ently of the door toward and from the keeper, and a loop member on the door and confining the latch to limit its movement toward the keeper.

6. In a hood fastener or the like, the com- 110 bination with a hinged member of an en- gine hood, of a keeper and latch hook mounted within the hood one on the hinged member and the other on a fixed support and relatively movable toward each other, a spring pressing the hook upwardly away 115 from its keeper, the latch movable inde- pently of its support toward and from the keeper, a loop member limiting the movement of the free end of the latch hook relative to the hood member, an operating 120 member movably associated with the hook and having a portion extending across the throat and below the beak of the hook, the operating member operable from without the hood to expel the hook from the keeper 125 in the act of opening the hood and to en- gage the hook with the keeper in the act of closing the hood.

7. In a device of the class described, the 130 combination with a hinged member of an

engine hood, of a stationary keeper within the hood, a hooked latch rod of round stock mounted within the hood on the hinged member and swinging therewith and also independently thereof to and from operable relation to the keeper, a spring pressing the hook longitudinally away from the keeper, the hooked end of the latch having a terminal portion curved gradually to form a gently inclined guide for directing the hook into engagement with the keeper, an operating rod likewise formed of round stock mov-
ably associated with the hook and having a portion extending across the throat and be-

low the beak of the hook, a handle connect-
ed with the hook and the operating mem-
ber and extending to the exterior of the
hood, and a loop mounted on the hinged
member and confining the latch to limited
swinging movement toward the keeper in-
dependently of the door. 15 20

In witness whereof I have hereunto signed
my name in the presence of two subscribing
witnesses.
